(57) **CLAIM**

The ornamental design for a headset with earhook, as substantially shown and described.

DESCRIPTION

FIG. 1 is a perspective view of the headset with earhook;
FIG. 2 is a right side view of the headset with earhook;
FIG. 3 is a left side view of the headset with earhook;
FIG. 4 is a front view of the headset with earhook;
FIG. 5 is a rear view of the headset with earhook;
FIG. 6 is a top view of the headset with earhook; and,
FIG. 7 is a bottom view of the headset with earhook.
The broken lines form no part of the claimed design.
